Attorney

UNITED STATES PATENT OFFICE.

ALPHIDA J. BOUTHILLIER, OF CRANSTON, RHODE ISLAND.

SHOE.

Application filed January 28, 1923. Serial No. 615,850.

To all whom it may concern:

Be it known that I, ALPHIDA J. BOUTHILLIER, a citizen of the United States, residing at Cranston, in the county of Providence and State of Rhode Island, have invented certain new and useful Improvements in Shoes, of which the following is a specification.

My invention relates to shoes, and more especially to shoes with an arch supporter receiving means constructed therein.

One object of my invention is to provide a shoe adapted to receive arch supporting means, usually comprising a plurality of flat separate filler members, underneath the inner-sole to build the shank high enough to furnish the desired amount of arch support to suit the individual needs of the wearer. Shoe manufacturers have not to date realized that roughly half the people who wear shoes actually need some means of arch support, and that some slight arch support is desirable for everyone. I am aware that formerly separate inner soles consisting of separate layers of fabric connected together have been built, provided with pockets adapted to receive separate filler members, but so far as I am aware, I am the first to provide a standard type of shoe complete in itself, which may be sold to everyone, and which contains of its own inherent structure some slight arch supporting means, which is at least not harmful to everyone, and which can be easily and readily built up in the shank thereof by the mere insertion of small, separate flat filler members in a pocket built right in the shoe readily available from either side to furnish the desired degree of arch support even for the worst type of broken down arches. As I merely insert a short half inner sole in a standard shoe without increasing the amount of stitching required, it is seen that the cost thereof is negligible, and that I provide one standard shoe at a slightly greater cost suitable for everyone, but especially suitable for and readily adaptable to the individual use of the fifty per cent of the people who actually need some form of arch support.

A further object of my invention is to provide a simple and easily constructed arch supporter, thus dispensing with the necessity of wooden, metal and other complicated

devices characteristic of former arch supporters.

These and such objects of my invention as may hereinafter appear will be best understood from a description of one embodiment thereof, such as is shown in the accompanying drawings.

In the drawings, Fig. 1 is a side elevation of my shoe, parts being shown in section.

Fig. 2 is a view similar to Fig. 1 with the shank filled up by the insertion of the separate filler members.

Fig. 3 is a section along the lines 3—3 of Fig. 2, illustrating how the inner soles are stitched to the welt.

Fig. 4 is a perspective view of one of the filler members.

In the drawings, wherein like characters of reference indicate like parts throughout, 1 is the upper, 2 the welt, 3 the usual inner-sole, 4 the outersole, and 5 the heel, these parts being similar to the parts used in standard shoes. I provide in addition the half innersole 6 which extends along the shank 7 from 8, any convenient line extending transversely of the heel 5 behind the front edge of the heel 5 to 9 any convenient line extending transversely of the ball 10 of the shoe. The half innersole 6 may completely cover the heel 5, but in the preferred embodiment shown to save leather I have only continued this as far back as absolutely necessary. The half innersole 6 is connected to the upper 1, the innersole 3 and heel 5 in any convenient fashion usually by means of the nails 11. From the heel 5 forward the half innersole 6 is connected to the upper 1 and welt 2 by two sets of stitchings 12 and 12^a, the set 12 extending along the inner outside edge of said half innersole 6 from the rear to the front edge thereof, and the set 12^a extending along the outer outside edge of the said half innersole 6 from the rear to the front edge thereof. Though in my preferred embodiment I have illustrated stitchings as the connecting means, it is obvious that any other form of suitable connecting means may be employed for connecting the outside edges of said half innersole 6 to the upper 1 and welt 2. The outersole 4 is connected to the welt 2 by the usual stitching 13, which extends from the inner side of the heel 5 all around the toe 14 to the outer side of the heel 5. On top of said

half innersole 6 is the usual innersole 3 which extends from the rear end of the heel 5 to the toe 14, as usual. The inner sole 3 is connected as explained to the upper 1 and heel 5 at the heel, and in my invention to the part of the extra half innersole 6 extending over the heel 5, in any convenient fashion, usually by means of the nails 11. From the front end of the heel 5 to the front edge 9 of the half innersole 6, the usual innersole 3 is not connected to the welt 2 at all, thus providing throughout the shank 7 a pocket 15 extending transversely the width of the shoe. Forward from the front edge 15 of the half innersole 6, the usual innersole 3 is connected along the outside edge thereof to the upper 1 and welt 2 as usual, in any convenient fashion, usually by means of the stitching 16, which extends along the outside edge thereof from the outside end 9^a of the front edge 9 of the half innersole 6 on the outer side of the ball 10, around the toe 14 to the inside end 9^b of the front edge of the half innersole 6 on the inner side of the ball 10. It is thus apparent that the innersole 3 will be attached to the upper 1 and welt 2 except at each side of the shank 7, where the sides of the innersole 3 will be unattached thus creating the pocket 15 extending longitudinally between the innersole 3 and the half innersole 6 and transversely the width of the shoe for the purpose hereinafter explained. As the innersole 3 will be raised slightly by the addition of the half innersole 6, and as, if the inner sole 3 is made of hard leather it may become warped so as to form at all times thereunder a small air pocket even when in use, it is apparent that some slight degree of arch support will at all times be furnished by my shoe, which is at least not harmful for everyone, and even desirable as tending to protect against the falling of the arches in later life.

45 As explained previously, it is for the fifty per cent of the people who actually have trouble with their arches and who need some form of arch support that my shoe is constructed. To aid them any convenient kind 50 of filling means may be inserted in the pocket 15 from either side to build up the shank 7 any required amount to satisfy the individual's needs. In the preferred form shown in Fig. 4 my preferred filling means 55 consists of separate filler members 17 usually made of flat or board leather, although they may be made from any suitable elastic material, such as rubber, felt, cork, etc. These are preferably wedge-shaped 60 and of no great thickness and are usually cut with a straight edge 18 and a curved edge 19, and are smoothed off or tapered in thickness as at 20 from the straight edge 18 to the curved edge 19. It is thus seen that 65 my improved filler members 17 are readily

insertable in the pocket 15 from either side of the shank 7, and that they may be inserted from either side thereof as desired, to build up the shank 7 to furnish the desired degree of arch support for the individual wearer, and will furnish the required amount of support at the sides thereof where it is most needed. It is thus seen that I have provided a shoe of simple construction provided with a readily available arch 70 supporter receiving means built therein, which may be readily and conveniently built up to suit the different arch supporting requirements of all types of wearers.

It is understood that my invention is not 80 limited to the specific embodiments shown, and that various deviations may be made therefrom without departing from the spirit and scope of the appended claims.

What I claim as new and desire to secure 85 by Letters Patent is:

1. In a shoe, the combination of the welt, the heel, an innersole attached as usual to the heel and to the welt from the ball to the toe, an additional half innersole underneath 90 said innersole extending from the heel to the ball, attached to the welt from the heel to the ball, said innersoles thus forming between them a pocket extending transversely 95 the width of the shoe accessible from either side of the shank, and filling means in said pocket.

2. In a shoe, the combination of the welt, the heel, an innersole attached to the heel and to the welt from the ball to the toe, an 100 additional half innersole underneath said innersole extending from the heel to the ball attached to the welt from the heel to the ball, said innersoles thus forming between them a pocket extending transversely the 105 width of the shoe accessible from either side of the shank adapted to receive filling means to build up the shank to furnish the desired amount of arch support to the wearer.

3. In a shoe, the combination of the welt, the heel, an innersole connected to the heel and to the welt from the ball to the toe by stitching extending along the outside edge of said innersole from one side of the ball around the toe to the other side of the ball, an additional half innersole underneath said innersole extending from the front edge of the heel to the ball, connected to said welt by two sets of stitchings, one set extending 110 along the outside edge of said innersole from the front edge of the heel to the ball, the other set extending similarly along the inside edge thereof, said innersoles thus forming between them a pocket extending transversely the width of the shoe accessible from 115 either side of the shank, and filling means in said pocket.

4. In a shoe, the combination of the welt, the heel, an innersole connected to the heel and to the welt from the ball to the toe by 120

stitching extending along the outside edge of the said innersole from one side of the ball around the toe to the other side of the ball, an additional half innersole underneath

5 said innersole extending from the front edge of the heel to the ball, connected to said welt by two sets of stitchings, one set extending along the outside edge of said innersole from the front edge of the heel to the ball, the 10 other set extending similarly along the inside edge thereof, said innersoles thus forming between them a pocket extending transversely the width of the shoe accessible from either side of the shank, adapted to receive

15 filling means to build up the shank to furnish the desired amount of arch support to the wearer.

5. As a new article of manufacture, a shoe constructed to receive in the shank portion 20 thereof underneath the innersole, arch supporting means, said means comprising separate thin, flat filler members provided with a straight edge and a curved edge, said filler members being gradually tapered from the 25 straight edge to the curved edge thereof, said members being readily insertable from either side of shank underneath the inner-sole tapered edge first.

6. In a shoe, the combination of the welt, 30 the heel, an innersole attached as usual to the heel and to the welt from the ball to the toe, an additional half innersole underneath said innersole extending from the heel to the ball, attached to the welt from the heel to the 35 ball, said innersoles thus forming between them a pocket extending transversely the width of the shoe accessible from either side of the shank, and filling means in said pocket, said filling means comprising sepa-

40 a straight edge and a curved edge, the straight edges thereof being placed in the outside edges of said pocket.

7. As a new article of manufacture, a shoe 45 constructed with an additional half inner-sole in the shank thereof, and provided with a pocket extending transversely the width of the shoe accessible from either side of the shank between said half innersole and the true innersole adapted to receive sufficient 50 separate filler members to build up the shank to furnish the desired amount of arch support to the wearer.

8. In a shoe, the combination of the welt, 55 the heel, an innersole connected to the heel and to the welt from the ball to the toe by stitching extending along the outside edge of said innersole from one side of the ball around the toe to the other side of the ball, an additional half innersole underneath said 60 innersole extending from the front edge of the heel to the ball, connected to said welt by two sets of stitchings, one set extending along the outside edge of said innersole from the front edge of the heel to the ball, the 65 other set extending similarly along the inside edge thereof, said innersoles thus forming between them a pocket extending transversely the width of the shoe accessible from either side of the shank, and filling means 70 in said pocket, said means comprising separate thin, flat filler members provided with a straight edge and a curved edge, said filler members being gradually tapered from the straight edge to the curved edge thereof, the 75 straight edges thereof being placed in the outside edges of said pocket.

In testimony whereof I affix my signature.

ALPHIDA J. BOUTHILLIER.
